UNITED STATES PATENT OFFICE.

HORACE MALTBY, OF STAPLETON, NEW YORK, AND ADRIAN K. GARDNER,
OF JERSEY CITY, NEW JERSEY.

METHOD OF ORNAMENTING WOVEN CLOTH FABRICS.

SPECIFICATION forming part of Letters Patent No. 288,249, dated November 13, 1883.

Application filed April 5, 1883. (No model.)

To all whom it may concern:

Be it known that we, HORACE MALTBY, a subject of the Queen of Great Britain, and a resident of Stapleton, in the county of Richmond and State of New York, and ADRIAN K. GARDNER, a citizen of the United States, and a resident of Jersey City, in the State of New Jersey, have invented a new and useful Improvement in the Method of Ornamenting Woven Cloth Fabrics; and we do hereby declare the following to be a full, clear, and exact description thereof, reference being had to the accompanying drawings, forming a part of this specification.

This invention consists in producing on a woven cloth fabric raised ornamentations, which are taken out of the body of the cloth without reducing its width; also, in the method or process of producing such raised ornamentations.

In the drawings, Figure 1 is a garment the cloth of which contains our improvement. Figs. 2 and 3 are pieces of cloth on which is produced the improvement. Fig. 4 is a cross-section of the piece of cloth shown in Fig. 2, taken through the line *x x*. Fig. 5 is a cross-section of the piece of cloth shown in Fig. 3, taken through the line *y y*.

In producing the said raised ornamentations we proceed as follows: There is first stitched onto the woven cloth fabric *c*, either before or after it is made up into garments, a piece of buckram or crinoline, *a*, the lines of stitching in the instance given being two parallel lines, *b b*, forming the boundaries of the portion of the cloth, *c*, to be operated on in producing the raised portion. There is then passed into the pocket thus made a former, *d*. The surface of the cloth *c* above this former *d* and between the lines of stitching *b b* being stretched is first wet. Then a hot iron is passed over such wet portion until the moisture is absorbed by the heat. Then the former *d* is to be withdrawn, and there is left a raised portion of the cloth *c* between said rows of stitching *b b*, which par-

takes of the shape in its contour of the former *d*. No other portion of the cloth fabric is shrunk or narrowed by reason of the operation. To produce the best effect, the buckram or crinoline *a* should not be sewed on on the bias: 50 An additional piece of buckram or crinoline, *e*, however, may be placed on the bias between the backing *a* and the cloth fabric, as seen in Fig. 3 of the drawings, and the former *d* is then inserted between the backing *a* and the buckram *e*. The piece *e*, being on the bias, will stretch upward with the section of the cloth *c*, and after the operation of wetting and ironing out and withdrawal of the former *d* the piece *e* will be found as a re-enforce to the 55 raised ornament, as seen in Fig. 5 of the drawings, and will help to preserve the shape of such ornament, especially if the cloth is fine and soft in its texture.

The former *d* may be of shape required for 60 the ornament to be produced on the surface of the cloth operated upon.

We claim—

1. The method of producing raised ornamentation on the surface of woven cloth fabrics 70 without reducing the surface thereof, consisting in securing a strip of backing to one side of the material to form a pocket, then moistening the fabric to be ornamented, inserting a former into the pocket, and applying heat 75 and pressure, and subsequently withdrawing the former, substantially as described.

2. A woven cloth fabric having raised ornamentations on its surface formed of the fabric itself and a backing consisting of a strip 80 of textile material stitched to the fabric along the boundaries of the raised portion thereof, and a re-enforcing strip of textile material attached to the fabric on a bias, substantially as shown and described.

HORACE MALTBY.

ADRIAN K. GARDNER.
